UNITED STATES PATENT OFFICE

1,967,635

MEANS FOR SUPPLYING PRINTING PRESSES
WITH SPECIAL PAPERIsidor Tornberg, Plainfield, N. J., assignor to Wood
Newspaper Machinery Corporation, New York,
N. Y., a corporation of VirginiaApplication February 21, 1931, Serial No. 517,467
Renewed January 5, 1934

5 Claims. (Cl. 270—18)

This invention relates to printing machinery and is particularly designed for the printing of newspapers in large plants.

The principal objects of the invention are to provide means whereby an auxiliary web can be fed into any unit of a press without unloading the usual reel and loading it up again with paper of a different width and to provide means whereby a change can be made from any width roll to a two-page wide roll, practically without delay.

Other objects and advantages of the invention will appear hereinafter.

Reference is to be had to the accompanying drawings, in which

Fig. 1 is an end view of a part of a printing press showing the auxiliary paper roll stand in a position adjacent thereto;

Fig. 2 is a plan of the same;

Fig. 3 is an end view showing the auxiliary paper roll mounted on a vertical axis;

Fig. 4 is a plan of the same, and

Fig. 5 is a plan showing the application of the invention to a plurality of printing units.

It is very often desirable to run in a special colored sheet in large newspaper printing plants to make a particular edition distinctive. Some papers change the color of their cover sheet two or three times each day for different editions. It is not always the practice to place this special colored paper in any one particular location in the paper. In the printing of different editions it very often happens that a change of edition calls for a change in the number of the papers of the product. At the present time it is a rather difficult and time-consuming task to unload a reel and load it up with paper of a different width. However, that is the way it has been done.

Referring to Figs. 1 and 2 it will be seen that a part of a printing press is shown involving a reel 11 for supplying paper of normal width to the press in a direct manner from the running web roll 12. This roll is located usually at the end of the press, or at least in alignment with it, so that no turning bars are used. Heretofore it has been necessary to take the rolls 12 off this reel and load it up with new rolls, usually of half width, when it was desired to print color sheets for the paper.

According to this invention, in addition to the reel 11 and its rolls 12 which remain in position all the time and are not unloaded, I provide an auxiliary reel 13 carrying web rolls 14, usually of half width and of a different color paper. This reel is supported on a carriage 15 which is

mounted on tracks 16 extending longitudinally of the press at one side thereof. The carriage 15 may be provided with rollers if desired to make it easier to run it along the track.

It will be seen that the reel 13 can be moved along this track to any desired unit of the press and the web run into the press over turning bars 17 which, of course, may be located as shown in Fig. 2 to run the paper in on the near side or can be located at the opposite side to run the paper in there. An automatic pasting device 18 can be employed with this auxiliary reel, of the same nature as those usually employed.

In the form shown in Figs. 3 and 4 the same results are secured where there is not room for a reel like that shown in Fig. 1. Here I provide a reel 20 on a frame 21 running along the same tracks 16 and having its web rolls 22 mounted to turn on vertical axes. The frame of the reel in this case is mounted on a vertical shaft 23 and the pasting device 18 can be used as in the other case. The same turning bars 17 are employed.

Thus I have provided for an auxiliary narrow paper roll stand for supporting the web rolls of the special or colored paper used to form covers or inserts for the newspaper for special editions and the like. This roll stand is arranged so that it can be moved along and finally located in any desired position along the line of press units. The paper therefore can be fed into any deck desired and the change for printing on the colored web can be made with practically no delay, leaving the usual reel 11 and its rolls 12 ready to feed into the press again when desired. Therefore, both the change to the color web and the change from it to the normal web is made with very little trouble and with practically no delay.

Although I have illustrated and described only two forms of the invention I am aware of the fact that other modifications can be made therein by any person skilled in the art without departing from the scope of the invention as expressed in the claims. Therefore I do not wish to be limited in this respect but what I do claim is:—

1. The combination with a printing press and means for supplying a full width web thereto, of an auxiliary web supply device located at the side of the press for supplying it with a web of a different width.

2. The combination with a printing press comprising a plurality of units and means for supplying a full width web thereto, of means movable along the press longitudinally thereof for supplying a narrower web to any desired unit of the press.

3. The combination with a printing press comprising a plurality of units and means for supplying a full width web thereto, of a track extending along the press, and an auxiliary web supplying device adapted to be moved along the press on said track to supply a different web to any desired unit of the press.

4. The combination with a printing unit, of means in alignment with the unit for supplying the usual web thereto, and means adjustable

along the side thereof for alternatively supplying a web of a different character to said unit.

5. The combination with a printing press and means for supplying a web thereto, of a rotatable magazine reel carrying rolls with their axes vertical and at one side of the first-named web supplying means for supplying an auxiliary web to the same press.

ISIDOR TORNBERG.
